MICHAEL REILLY, OF COVINGTON, KENTUCKY.

Letters Patent No. 67,675, dated August 13, 1867.

IMPROVED TRACE-SUPPORTING HOOK.

The Schedule referred to in these Letters Patent and making part of the same.

TO WHOM IT MAY CONCERN:

Be it known that I, MICHAEL REILLY, of Covington, Kenton county, Kentucky, have invented a new and useful Trace-Supporting Harness Hook; and I hereby declare the following to be a full, clear, and exact description thereof, reference being had to the accompanying drawings, making part of this specification.

The object of this invention is to provide a harness fastening having various applications, and combining the security of a buckle with the convenience of a common hook. In the accompanying drawings—

Figure 1 represents some portions of harness embodying my invention.

Figure 2 is a modification of the same.

Figure 3 is a front view of the hook-buckle, and

Figure 4 is a side view of the same in section.

A is a frame, which is riveted fast to any part of the harness desired, having a socket for the introduction of a pin, *a*, which traverses a suitable socket in the hook *B*.

In fig. 1 the device is shown attached to the hame *C*, back-band *D*, belly-band *E*, and hip-strap *F*, in each of these places being used to connect the trace to these parts respectively. In fig. 4 a slight modification is shown, in which the plate *A* is somewhat altered in form, and the pin *a* elongated and curved so as to allow room for the hook *B* and diagonal strap *G* to be fastened upon it, this taking the place of the breeching-ring.

In attaching the trace to the hook the point *b* is drawn outward and the link passed over it, when it is released, and the pressure of the leather backing upon the side of the hook will again place the point *b* within the recess of the plate *A*, so that by no probable contingency or accident can the link become unhooked.

Some of the advantages claimed for this buckle-hook are as follows: That as the frame *A* can be riveted fast to the leather it will obviate the necessity of much work in the way of stitching, which has heretofore been unavoidable; that this hook is applicable to places where leather will soon cut off, namely, at the end of the hip-strap *F*, breeching-ring, back-band *D*, and belly-band *E*.

It has heretofore been customary to tie the breeching-ring and hip-strap fast to the trace by a leather thong, which nipping between the links and being abraded by them soon cuts off, and also when a change from one link to another is desired the hard-tied leather yields with difficulty, if at all, to the operator, whereas the operation of shortening or lengthening the trace with this hook is done without any difficulty.

I do not confine myself to the applications of my hook here shown, as the same is applicable in some other positions.

I claim herein as new, and of my invention—

The trace-supporting hook for harness, consisting of parts *A* & *B* and *b*, substantially as set forth.

In testimony of which invention I hereunto set my hand.

MICHAEL REILLY.
